TO ALL WHOM IT MAY CONCERN:

Be it known that I, F. W. This invention relates to a design for a cast-metal wall-bracket, in imitation of carved wood, and the design consists of a frame, which forms a base against the wall for the support of the shelf, the said frame being ornamented above and below the shelf by the introduction of foliage and other tracery, and a brace turning from the base outward to the centre, to support the shelf, and that ornamented to correspond to the frame, the whole a clearly shown in the accompanying illustration.

Having thus fully described my invention, what I claim as new, and desire to secure by Letters Patent, is—
